RECEPTACLE CART

Tony J. Bongiorno, 7 Munson Lane, West Sayville, N.Y.

Filed Apr. 6, 1965, Ser. No. 84,625

Term of patent 14 years

(Cl. D14—3)

FIG. 1

FIG. 3

FIG. 4

FIG. 1 is a perspective view of a receptacle cart showing my new design, the container shown in broken lines being included for illustrative purposes only;

FIG. 2 is a side elevational view thereof taken from the same side as that shown in FIG. 1;

FIG. 3 is a rear elevational view thereof;

FIG. 4 is a top plan view thereof.

I claim:

The ornamental design for a receptacle cart, as shown and described.
